TIME-FUSE.

No. 844,222.

Specification of Letters Patent.

Patented Feb. 12, 1907.

Application filed February 10, 1906. Serial No. 300,475.

To all whom it may concern:

Be it known that I, KARL WIESER, a subject of the Emperor of Germany, and a resident of Essen-Rüttenscheid, Germany, have invented certain new and useful Improvements in Time-Fuses, of which the following is a specification.

The present invention relates to those mechanical time-fuses which are timed through the medium of a readily-rotatable cap covering the fuse mechanism, and has for its object to construct the cap in such a manner that it automatically becomes fixed on firing.

In the accompanying drawing, which is an axial section of the forward part of a shell having the fuse applied, the invention is shown, by way of example, as embodied in the fuse forming the subject-matter of United States Patent No. 728,151 to Carl Bäker.

The construction and mode of operation of the fuse mechanism is old, as also is the means through which adjustment of the time of ignition results from turning the cap A. It is therefore unnecessary to further discuss these features. The timing-cap A is so easily rotatable on the cylindrical trunnion or seat b' of the fuse-body B that it can be adjusted by hand without the use of a key or the like. Pins C, which are screwed into the cap A, engage in an annular groove b² in the trunnion b' and prevent axial displacement of the cap. In the part of the cap A which surrounds that portion of the trunnion b' located in advance of the groove b² is provided an annular groove a', so that the wall of the cap at this point is considerably weakened.

At the moment of firing a projectile provided with this improved fuse the portion of the cap weakened by the groove a' yields to the force of inertia of the part of the cap that

is in advance of the groove and is upset and packs or permanently binds against the trunnion b' in such a manner that the cap is unable to turn upon the trunnion when the projectile commences to rotate and the adjustment of the cap is maintained and untimely bursting of the projectile avoided.

Having thus described my invention, what I claim, and desire to secure by Letters Patent, is—

1. A time-fuse having a circumferentially-adjustable setting means adapted to yield under the force of its inertia to be retarded relatively to the forward movement of a projectile, at the time of firing, and constructed to interlock by such yielding, against movement in the direction of its adjustment.

2. A time-fuse, having a rotatably-adjustable cap constructed to yield under its own inertia and bind against a relatively fixed part, at time of firing.

3. A time-fuse comprising a fuse-body, and a cap rotatably adjustable on the fuse-body and having its wall weakened to permit the cap to yield at the weakened place at time of firing, under the inertia of a part of the cap, and cause the cap to bind against the fuse-body.

4. A time-fuse, provided with a seat and a cap, between which there is rotary adjustment in timing the fuse; said cap having a circumferential groove in its wall surrounding said seat, to permit the portion of the cap thus weakened, to yield, on firing, under the inertia of the part of the cap in advance of the groove, and to permanently bind against said seat.

The foregoing specification signed at Düsseldorf this 18th day of January, 1906.

KARL WIESER.

In presence of—

WILLIAM ESSENWEIN,
PETER LIEBER.
